UNITED STATES PATENT OFFICE.

THOMAS J. LINDSAY, OF BALTIMORE, MARYLAND, ASSIGNOR OF ONE-THIRD
TO WILLIAM F. MORROW, OF SAME PLACE.

FIRE-ESCAPE.

SPECIFICATION forming part of Letters Patent No. 538,615, dated April 30, 1895.

Application filed February 14, 1895. Serial No. 538,347. (No model.)

To all whom it may concern:

Be it known that I, THOMAS J. LINDSAY, a citizen of the United States, residing at Baltimore, in the State of Maryland, have invented certain new and useful Improvements in Fire-Escapes, of which the following is a specification.

This invention relates to a portable fire escape, for use in private residences and hotels and which is adapted to be folded compactly so as to occupy but little space and admit of being carried with wearing apparel in an ordinary traveling trunk.

The invention is illustrated in the accompanying drawings, in which—

Figure 1 is an elevation showing a section of a wall of a house and illustrating the improved fire-escape as it appears when attached to a window-sill. Fig. 2 is a view, on a large scale, of the adjustable clip or saddle for window-sills. Fig. 3 shows the outside jointed prong of the clip or saddle. Fig. 4 is a view of a clip or saddle for the window-sill, in which the prongs are rigid.

The fire escape comprises a folding basket or cage; an improved clip or saddle to take astride of a window sill; and a pulley and cord connecting between the said basket and the saddle.

The basket or cage, A, is made of cotton duck or other suitable flexible material. It is slightly tapering, being smaller at the bottom, and pieces of thin board, b, may be placed in the basket upon the bottom and serve for a person to stand on. The top edge of this basket has attached to it a jointed hoop, C. The hoop is made in two sections, d, d', united at diametrical points by knuckle joints, e, placed with the "knuckle" or stop part, e', of the

joint upward. By this construction the two sections, d, d', of the hoop may tilt at the center and both sections turn down toward the bottom of the basket; but cannot tilt from the center upward. A rod, f, extends diametrically across the top of the basket in a transverse direction with respect to the two joints, e, and the ends of the cross rod connect with or engage the two hoop-sections, d, d'. This rod, f, has one end jointed or hinged, as at f', to one section, d, and the other end has a hook, f², which engages an eye, g, on the

other section, d'. At its center this cross rod has an eye, h, to which the lowering cord or rope, i, is made fast.

It will be seen that the cross rod, f, is so engaged with the two jointed hoop-sections that when suspended from the lowering rope it is impossible for the said jointed hoop to fold on its joints, e.

The clip or saddle, J, sets astride of the window-sill K, and has an eye, l, with which engages the link or eye, m, of a pulley-block, n, and the rope, i, passes over the pulley in this block.

It will be seen that the basket or cage, A, may, at the outset, be quite close to the window-sill and thus render it comparatively easy for a person in the window to take position in the basket, and when once in the basket the person may lower himself by paying out the rope which is coiled in the basket.

The clip or saddle, J, may be an integral piece having two prongs, o, p, as in Fig. 4, or it may be, and by preference is, both jointed and adjustable, as in Fig. 2. The form shown in this figure has the outer prong, o, connected with the top or saddle bar by a knuckle-joint, q, to enable it to fold and take position parallel with said top or saddle bar. This latter has a down-curved eye, l, which serves two purposes,—first, as a stop for the pivoted prong, o, and limits its outward movement, and, second, for the attachment of the link or eye, m, of the pulley-block. The prong, p, which takes on the inner side of the window sill, is made adjustable on the top or saddle bar. This prong has at its upper end a slot, r, through which the said top bar passes loosely or freely. The top bar has a number of holes, s, and a pin, t, passed down into any one of said holes enables the prong, p, to be set or adjusted along the top bar to suit or fit on walls or window sills of different thicknesses.

To fold up this fire escape and put it in the most compact form, the cross-rod, f, of the basket has its end unhooked, the top hoop is folded on the joints, e, and then the flexible basket is closely folded. The clip or saddle has the inner prong, p, slipped off and the outer prong, o, folded. These parts are then laid with the folded basket and coiled rope.

Instead of a cross-rod, f, connecting the two

hoop-sections at points which are on a line in a transverse direction with respect to the said two joints, it is obvious the lowering rope itself may be so connected to the two sections, or a 5 separate piece of rope or chain may extend across.

Having thus described my invention, what I claim as new, and desire to secure by Letters Patent, is—

- 10 1. In a fire escape, the combination of a saddle having two prongs to set astride of a window-sill and provided with an eye for attachment of a pulley; a basket composed of flexible material; a hoop made in two sections united by a knuckle joint with the stop part of the joint upward—said hoop attached to the basket; and a rod extending diametrically across the top of the basket in a transverse direction with respect to said joints and the two ends 15 of said rod engaged with the two hoop-sections; and a lowering rope passed over said pulley and attached to the basket.
- 20 2. In a basket or cage for fire escapes, the combination of a basket composed of flexible material; a hoop made in two sections united by a knuckle joint with the stop-part of the

joint upward—said hoop attached to the basket; and a rod extending diametrically across the top of the basket in a transverse direction with respect to said joints and the two ends 30 of said rod engaged with the two hoop-sections.

3. In a fire escape, the combination of a folding adjustable saddle bar to sit horizontally upon a window sill, an outer prong, *o*, adapted 35 to engage the outer side of the sill and jointed to the outer end of the saddle bar so as to fold parallel with the under side of said bar, another prong, *q*, to engage the inner side of the sill and having a slot through which the saddle bar is adjustable, and a down-curved eye also on the outer end of the bar and serving as a stop to limit the outward swing of said jointed prong; a pulley block suspended from said eye; a basket; and a lowering rope passed 40 over the pulley and attached to the basket.

In testimony whereof I affix my signature in the presence of two witnesses.

THOMAS J. LINDSAY.
